Primary Examiner — Calvin E Vansant(74) *Attorney, Agent, or Firm* — Birch, Stewart, Kolasch & Birch, LLP(57) **CLAIM**

The ornamental design for a shelf for indoor plant cultivator, as shown and described.

DESCRIPTION

FIG. 1 is a top perspective view of a shelf for indoor plant cultivator showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a perspective view showing the shelf for indoor plant cultivator in a state of use.

The broken lines depict portions of the shelf for indoor plant cultivator that form no part of the claimed design.

1 Claim, 7 Drawing Sheets(56)
